REGISTRATION FRAME

Richard M. Haff, Binghamton, N. Y., assignor to
 General Aniline & Film Corporation, New York,
 N. Y., a corporation of Delaware

Original application July 18, 1944, Serial No.
 545,447. Divided and this application October
 10, 1945, Serial No. 621,452

3 Claims. (Cl. 164—85)

1

This application pertains to a registration frame for perforating negatives or other photographic transparencies after they have been brought into registration and prior to printing them. The case is a division of copending application Serial No. 545,447, filed July 18, 1944 now Patent 2,418,226, granted April 1, 1947, to R. M. Haff.

Extreme accuracy is required when printing from color separation negatives, and that is especially true when projection printing methods are employed. The greater the scale of enlargement, the more inaccuracies in registration or printing are magnified. Accordingly, it is a general purpose of the device herein described and claimed to provide for accurate registration of negatives to be printed and perforation of these negatives so that they may be separately handled in the subsequent printing.

Enlarging in color work differs from the same process as applied to black and white photography in that a plurality of negatives known as color separation negatives must be independently projected on to the enlarging paper, for example, any suitable color paper. In most all instances, at least three such negatives must be made and separately projected, each with its own particular color of light.

For accomplishing that purpose in the typical projection printer or enlarger now available, the invention of the instant case provides a simple registration and perforating frame such as may be easily employed by those reasonably skilled in photographic work and which is especially adapted to use with smaller negatives such as are more likely to be involved if enlarging is to be done rather than contact printing.

The invention is described herein by reference to a specific embodiment of the same as illustrated in the accompanying figures of drawing wherein:

Fig. 1 is an isometric view of the base member of the registration frame.

Fig. 2 is an isometric view of the cooperating cover member.

Fig. 3 is a detail of one type of punch employed with the frame.

Fig. 4 is a detail of another punch adapted to making a circular hole rather than an elongated hole as with the punch shown in Fig. 3.

Now referring to the Figs. 1 and 2, the registration frame consists of two cooperating parts each having a transparent or translucent window between which the negative or negatives to be punched or registered are clamped and by means

2

of which light projected from the opposite side of the frame and negatives will serve to illuminate them so that the images thereon may be brought into accurate registration. The frame includes, among other parts, a base 10 at the upper side of which is inserted a window 11 retained by means of the clips 12 and 13. The window preferably is set so that its top surface projects slightly above the surface of the frame itself, and the clips 12 and 13 engage within beveled notches so that they are entirely beneath the top surface of the window.

The cover member includes a frame 14 in which a window 15 similar to the window 11 is set, said window projecting below the lower surface of frame 14 and being retained in the same or another convenient manner. The projection of the windows slightly above and below the frame surfaces is for the purpose to assure good contact with the film material inserted therebetween. Frame 14 has at each corner, or at least at two spaced points, dowel pins 16 which are accurately engageable within the holes 17 in frame 10. These pins assure accurate positioning of the cover member over the base member after each removal of the same and also assure accurate registration of the punch guiding openings and the cooperating die openings in the base. The cover is held in position above the base or may be drawn down for clamping a negative or negatives between the windows 11 and 15 by means of two screws 18 and 19, each of which has a knurled head and a collar, the latter being indicated by numerals 20 and 21. These screws engage within tapped holes 22 and 23 in the base and may serve to hold the cover slightly raised from the base during manipulation of the negatives to bring them into registration, or may serve to draw the cover down for temporarily clamping the negatives in position while the perforations are punched in them. Spring clips 24 and 25 engage beneath the knurled heads of the screws but above the collars 20 and 21, and thereby retain them in proper position for effecting either of the above-mentioned results.

The frame 14 of the cover member is slotted or apertured at 26 so that edges of the negatives may be reached for moving them in the appropriate direction while effecting their registration. The cover member actually acts as a template by means of which the punches are positioned. For that purpose a circular opening 27 at one corner and an elongated opening 28 at the opposite corner align with similar die open-

ings 29 of circular cross section and 30 of elongated section in the base member, Fig. 1.

In Figs. 3 and 4, the punches are shown, one being of circular section and the other elongated correspondingly to the openings 28 and 30. The elongated punch indicated at numeral 31 has a handle 32 while the circular punch has a similar handle 34. These punches are accurately ground and have only a working clearance in the openings provided for them in the cover and base members.

Operation

It is to be assumed that color separation negatives have been made according to some one of the accepted methods. These negatives may or may not have indexing or registration marks thereon, and, accordingly, registration will be effected by bringing the marks into coincidence or by bringing the images into proper registration. One of the negatives is first placed on the glass plate 11 and should be taped in position by using some thin, transparent type of adhesive tape. The cover is then placed over the base member of the registering frame, clamped down by using the screws 18 and 19, and that negative then perforated using the punches 31 and 33. The cover is then raised away from the base member and a second negative superimposed upon the first. The cover member should be held away from contact with the negatives, or at least, should not interfere with the manipulation of the second negative so long as it is being moved to effect registration. The openings 26 facilitate this function, and pointed instruments of any convenient type may be used therethrough to engage the second negative and move it into registry with the first negative. When the image on the second negative is brought into exact coincidence with that on the first, the cover is again clamped in position to retain that registration and the second negative may then be perforated.

The second negative is then removed and the third treated in like manner, and this is continued with as many negatives as are to be printed for that particular picture. When completed, they are laid aside and properly marked or arranged so as to be printed in predetermined sequence and with the appropriate color of light for each. During the registration, the frame should be illuminated from the under side of the window 11 and, if desired, magnifying means may be employed to effect greater accuracy. Magnifying means is also desirable for eliminating errors due to parallax.

While one embodiment of the invention has been disclosed, it is to be understood that the inventive concept may be carried out in a number of ways. This application is thereby not to be

limited to the precise details described but is intended to cover all variations and modifications thereof falling within the spirit of the invention and the scope of the claims.

5 I claim:

1. A registration frame for photographic negatives including a base and a cover member, a translucent window in each, positioning means by which said cover may be superimposed in a definite position over the base member, means for holding the cover slightly above or for clamping it against the base, punch guiding openings and die openings in alignment therewith, the former in the cover and the latter in the base, and a 10 punching means for insertion in said openings, said means including at least one circular punch and one elongated punch.

2. A registration frame for photographic negatives including a base and a cover member, a translucent window in each, positioning means by which said cover may be superimposed in a definite position over the base member, means for holding the cover slightly above or for clamping it against the base including tapped holes in 15 the base and cooperating threaded elements retained by the cover, said threaded elements having a knurled head and an annular collar between which engages a positioning clip, punch guiding and die openings in said cover and base, 20 and punch means for insertion in said openings.

3. A registration frame for photographic negatives including a base and a cover member, a translucent window in each, means including dowel pins in one member and cooperating openings in the other member by which said cover may be superimposed in a definite position over the base member, means for holding the cover slightly above or for clamping it against the base, which means comprises tapped openings in the 25 base and cooperating screws held against axial movement within clips in the cover, punch guiding openings in the cover and die openings in alignment therewith in the base, and punching means for insertion in said openings, said punching 30 means including at least one circular punch and another punch of elongated cross section.
